John E. Miller

UNITED STATES PATENT OFFICE.

JOHN E. MILLER, OF DENVER, COLORADO.

BADGE-MEDALLION.

SPECIFICATION forming part of Letters Patent No. 702,737, dated June 17, 1902.

Application filed October 14, 1901. Serial No. 78,577. (No model.)

To all whom it may concern:

Be it known that I, JOHN E. MILLER, a citizen of the United States of America, residing at Denver, in the county of Arapahoe and 5 State of Colorado, have invented certain new and useful Improvements in Badge-Medallions; and I do declare the following to be a full, clear, and exact description of the invention, such as will enable others skilled in the 10 art to which it appertains to make and use the same, reference being had to the accompanying drawings, and to the figures of reference marked thereon, which form a part of this specification.

15 This invention relates to improvements in badge-medallions and means for attaching the same.

The object of the invention is to produce a device of this character which is simple in 20 construction and easily and cheaply manufactured, the parts constituting the same being formed and assembled by suitably-constructed implements, the whole operation requiring but a very short time.

25 The invention further consists in the novel construction and means of attaching a medallion, as will be fully set forth in the accompanying specification, and particularly pointed out in the claims.

30 In the accompanying drawings, forming part of this application, Figure 1 is a view illustrating a medallion secured to a badge. Fig. 2 is a vertical sectional view taken through the medallion and badge. Fig. 3 is a plan view of the blank from which the casing of 35 the medallion is formed, showing V-shaped tongues or spurs struck out from the metal. Fig. 4 is a vertical sectional view showing the parts constituting the medallion in position to be assembled. Fig. 5 is a vertical sectional view of the completed article.

Like letters of reference indicate corresponding parts in the several figures.

Referring to the drawings, the numeral 1 indicates a circular disk or blank of sheet metal—such as brass, aluminium, or any preferred kind—which is stamped from a sheet of metal by suitably-constructed implements. From this blank the casing of the medallion 45 and means for attaching the same to a piece of fabric are formed, as will be fully shown. The blank 1 is placed in a suitable die, which

has a circular face of smaller diameter than the blank, and a stamp of the same diameter of the die is forced against the disk, forming 55 a rim 3 around the circumference thereof, as will be seen by reference to Fig. 4. The blank is then placed in another die, and by the action of a stamp, the surface of which is provided with a pair of oppositely-disposed punches, 60 a pair of V-shaped tongues or spurs 2 are formed, as shown in Fig. 3, which can be bent out for a purpose to be hereinafter referred to. A disk 4, of celluloid, of a size to fit within the rim 3 formed on the blank, is next employed, 65 and upon one side of the same a disk of paper 5 of the same diameter, bearing a suitable picture, insignia, or design, is placed so that the said picture or design shall lie next to or against the celluloid. The celluloid disk, 70 with its paper backing, is next subjected to the action of a suitable former, which is designed to give the said disk a concavo-convex form and which is heated to a sufficient degree to cause the disk to retain its form. 75 This disk is then placed within the rim 3 formed on blank 1, and the said blank is subjected to the action of a stamp and die by which it is given a concavo-convex form, and the rim 3 is pressed down so as to overlie the celluloid disk, and by subjecting the article to the action of the before-mentioned former the backing and disk are pressed in close contact with each other and given the finished form. The article is now complete, 80 and when it is desired to attach the same to a badge or to any suitable fabric the tongues or spurs 2 are passed through the fabric and are then bent to the position shown in Fig. 2, by which means the medallion is easily and 85 firmly secured. In this manner a pin is dispensed with and the time and expense of securing the same upon the medallion are saved. 90

The medallion may be secured at the end of the badge or at any point desired, and the 95 badge is secured at its upper end to the garment of the wearer by a pin of any preferred design. The device thus produced forms a neat and substantial article and one which can be easily and cheaply made, and the employment of the tongues or spurs 2 prevents the medallion from being accidentally or unintentionally detached from the badge.

Having thus fully described my invention,

what I claim as new, and desire to secure by Letters Patent, is—

In a badge-medallion, the combination with a badge, of a single piece of sheet metal, comprising a concavo-convex disk, stamped out of sheet metal and having its peripheral edge bent upon itself toward the convex side of said disk to form an introverted rim integral with the back, in combination with a flexible transparent disk of celluloid or other suitable material secured against the convex side of

15 said disk by said introverted integral rim, and tongue portions stamped free from said concavo-convex disk, and arranged and adapted to be inserted through and fastened to said badge, substantially as described.

In testimony whereof I affix my signature in presence of two witnesses.

JOHN E. MILLER.
